IDA C. A. BOSWORTH AND OSCAR R. CHESNUTWOOD, OF SEATTLE, WASHINGTON.

DESIGN FOR A HEAD FOR CANES, PINS, OR SIMILAR ARTICLES.

No. 39,716.

Specification for Design.

Patented Dec. 22, 1908.

Application filed May 7, 1908. Serial No. 431,539. Term of patent 3½ years.

To all whom it may concern:

Be it known that we, IDA C. A. BOSWORTH and OSCAR R. CHESNUTWOOD, citizens of the United States, residing at Seattle, in the county of King and State of Washington, have invented a new, original, and ornamental Design for Heads for Canes, Pins, or Similar Articles, of which the following is a specification, reference being had to the accompanying drawing, forming a part hereof.

In the said drawing, Figure 1 is an eleva-

tional view taken in the direction of the arrow in Fig. 2; and Fig. 2 is a like view taken in the direction of the arrow in Fig. 1.

We claim:

The ornamental design for a head for canes, pins, or similar articles, as shown.

IDA C. A. BOSWORTH.

OSCAR R. CHESNUTWOOD.
